UNITED STATES PATENT OFFICE.

WILLIAM L. BUTCHER, OF BRINGHURST, INDIANA.

FENCE PROTECTOR.

1,406,929.

Specification of Letters Patent. Patented Feb. 14, 1922.

Application filed April 21, 1921. Serial No. 463,150.

To all whom it may concern:

Be it known that I, WILLIAM L. BUTCHER, a citizen of the United States of America, residing at Bringhurst, in the county of 5 Carroll and State of Indiana, have invented certain new and useful Improvements in Fence Protectors, of which the following is a specification.

This invention relates to certain new and 10 useful improvements in fence protectors and has particular reference to a device adjustably connected to a fence post for supporting a strand of barb wire laterally of the fence construction to prevent animals from 15 coming in contact with the fence.

The primary object of the invention resides in the provision of an adjustable bracket secured to a fence post for supporting a strand of barb wire laterally of the 20 fence construction, the bracket including an arm having the barb wire secured thereto with the arm capable of being shifted to project on either side of the fence.

A further object of the invention has reference to a fence protector wherein an arm is adjustably secured to a bracket secured to a fence post with a barb wire attached to the outer end of the arm, the arm being adjustable to project laterally at opposite 30 sides of the fence and further capable of various angle adjustments, to lie either in a horizontal plane or in inclined planes of different degrees.

It is a further object of the invention 35 to provide a fence protector of the type above set forth with detailed improvements over the construction disclosed in prior patents granted to me on January 29, 1918, Patent No. 1,254,653 and August 27, 1918, Patent No. 1,276,718, the supporting bracket 40 for the barb wire supporting arm being of simplified construction with the wire supporting arm capable of various angular adjustments relative to the bracket as above 45 set forth.

With the above general objects in view, and others that will appear as the nature of the invention is better understood, the same consists of the novel form, combination and 50 arrangement of parts hereinafter more fully described, shown in the accompanying drawings and claimed.

In the drawings, wherein like reference characters indicate corresponding parts 55 throughout the several views,

Figure 1 is a perspective view of the fence

protector shown in operative position upon a fence post, the post, fence wires and barb wire being broken away,

Figure 2 is a front elevational view of the 60 fence protector, shown in operative position upon the upper end of a post with various adjustments of the barb wire supporting arm shown by dotted lines, and

Figure 3 is a horizontal sectional view 65 showing the bracket secured to the fence post and the wire clip for holding the bracket arm in adjusted angular positions.

Briefly described, the invention aims to provide a fence protector embodying an arm 70 adjustably mounted on a fence post for supporting a barb wire at the outer end thereof, to be positioned laterally of the fence construction to protect the fence from cattle attempting to jump the same, the barb wire 75 holding the cattle at a safe distance from the fence. The bracket arm is pivotally mounted on a bracket secured to the post and is capable of swinging movement to project laterally at either side of the fence, a wire 80 clip being associated with the bracket and bracket arm for holding the same in horizontal positions at either side of the fence or in upwardly inclined or perpendicular positions. The bracket embodies an angle 85 iron secured by a central bolt to a fence post with downwardly converging braces secured at their lower ends to the post to prevent movement of the angle iron relative to the post. The bracket arm has a 90 slotted opening in the inner end thereof for pivotal mounting upon the bolt for anchoring the angle iron to the post, the arm being slidable on said bolt, a limited distance, to permit pivotal movement of the arm on the 95 angle iron so that the same may move to a horizontal position for lateral projection at either side of the post. The brace bars and angle iron are provided with a series of openings while a single opening is formed 100 in the bracket arm adjacent its pivotal mounting, a U-shaped clip having the ends thereof selectively received in openings in the brace bars, angle iron and bracket arm for holding the bracket arm either in horizontal positions, and inclined or perpendicular 105 positions.

Describing the invention more in detail there is illustrated a fence post 1 that may be formed of either metal, concrete or wood 110 having usual fence wires 2 secured thereto by fasteners 3, the fence posts being placed

the desired distance apart with the usual number of strands of fence wire 2 secured thereto.

The fence protector embodies a bracket 5 formed of an angle iron horizontally positioned as shown in Figs. 1 and 2, the flange 4 of the angle iron being secured to the post 1 by the bolt 5, shown more clearly in Fig. 3, while the flange 6 of the angle iron projects at right angles to the flange 4 and is directed outwardly of the post 1. A pair of downwardly converging brace bars 7 are offset, or otherwise secured as at 8 to the flange 4 of the angle iron with their lower 10 meeting ends secured to the fence post 1 by the bolt 9. The flange 4 of the angle iron is provided with a plurality of spaced openings 10 while spaced openings 11 are formed in the brace bars 7, for purposes 15 presently to appear.

A relatively long bracket arm 12 is provided at its inner end with an elongated slot 13 for pivotal mounting on the bolt 5 that secures the angle iron of the bracket 25 to the post 1, the outer end of the arm 12 being provided with a slotted opening 14 while a terminal notch 15 is cut in the outer end of the arm. As shown in Figs. 1 and 2 a strand of barb wire 16 extends through 30 the end notch 15 of the bracket arm and is anchored therein by the binding clip 17.

A U-shaped clip 18 is associated with the bracket and bracket arm for holding the same in a fixed position, one of the ends 18' of the U-shaped clip being selectively received in the bracket openings 10 and 11 with the other end thereof entering an opening 12' in the arm 12, adjacent the pivoting slot 13.

40 When the bracket arm 12 is in the horizontal position shown in Fig. 1, said arm is moved on said bolt 5 to prevent upward tilting of the arm with the lower side of the arm supported in the flange 6 of the angle iron, and when so positioned, the opening 12' in the arm will register with the outer opening 10 in the angle iron, one end 18' of the clip 18 being received in said registering openings while the other end thereof is received in an opening in the adjacent brace bar 7, as clearly shown in Fig. 1, thereby rigidly anchoring the arm 12 against movement relative to the supporting bracket. In this position of the arm, the barb wire 55 16 projects a considerable distance to one side of the fence 2 and will effectively protect the fence from cattle confined therein, the lateral disposition of the barb wire preventing cattle from coming in close range 60 of the fence and also preventing the cattle from jumping over the fence. Should it be desired to project the bracket arm 12 from

the opposite side of the fence as illustrated by dotted lines in Fig. 2, the clip 18 is detached from the bracket and arm and the arm moved until the bolt 5 is received in the outer end of the slot 13, at which time the arm will be free to swing to the opposite side of the fence, and there retained in the same manner as illustrated by full lines in Fig. 1. With this adjustment it is also possible to elevate the arm 12 at an inclination by placing the clip 18 in desired openings 11 of the brace bar 7 or the openings 10 in the angle iron 4 with the other end of the clip received in the opening 12' of the bracket arm. Further, should it be desired to increase the height of the fence the arm 5 may be shifted to the perpendicular position shown by dotted lines in Fig. 2 with the clip 18 received in the inner openings 10 of the angle iron and the openings 12' of the bracket arm. With this mounting of the bracket arm on the bracket various adjustments thereof are capable of attainment as will at once be obvious, the bracket being of extremely simple construction, inexpensive to manufacture, and embodying comparatively few parts that are practically safe from injury.

90 What is claimed as new is:—

1. A fence protector comprising a bracket formed of an angle iron, a bolt securing the angle iron to a post, brace bars carried by the angle iron and secured to the post, a bracket arm pivotally mounted on said bolt and resting upon one flange of the angle iron when in a horizontal position, a barb wire secured to the outer end of said arm, and a clip associated with said arm and bracket for holding the arm in adjusted position.

2. A fence protector comprising a bracket formed of an angle iron, a bolt securing the angle iron to a post, brace bars carried by the angle iron and secured to the post, a bracket arm pivotally mounted on said bolt and resting upon one flange of the angle iron when in a horizontal position, a barb wire secured to the outer end of said arm, said pivotal mounting of the arm including a slot in the arm to permit the arm to be moved in one direction to prevent pivotal movement thereof and to be moved in the opposite direction to permit the arm to swing from one side of the fence post to the other side thereof, said angle iron and brace bars having a series of openings therein, there being an opening in said bracket arm, and a clip selectively positioned in said openings for holding the bracket arm in adjusted positions.

In testimony whereof I affix my signature.

WILLIAM L. BUTCHER
